CLAIM

The ornamental design for a portable, figure-reducing roller exerciser, as shown and described.

DESCRIPTION

FIG. 1 is a front elevational view of a portable, figure-reducing roller exerciser showing my new design; FIG. 2 is a top plan view thereof; FIG. 3 is a rear elevational view thereof; FIG. 4 is a bottom plan view thereof, and FIG. 5 is an end elevational view thereof, the end opposite being substantially a mirror image.

FIG. 1

FIG. 2
